APPARATUS FOR ANNEALING COILED STRIP

James D. Burby, Hastings-on-Hudson, N. Y., and James L. Whitten, Cleveland, Ohio, assignors to Anaconda Wire and Cable Company, New York, N. Y., a corporation of Delaware

Application April 8, 1940, Serial No. 328,466

6 Claims.

(Cl. 266—5)

This invention relates to the art of annealing metal and, in particular, to apparatus for annealing coils of metal in strand form such as wire, strip, or the like.

It has been customary heretofore to employ cover type furnaces for the annealing of coils of wire, strip and the like. A complete installation comprises a plurality of furnace bases, e. g., four, and a heating cover or furnace bell adapted to be disposed upon the bases successively, to heat coiled material thereon to the proper temperature for annealing. After the material is heated to the proper temperature, the heating cover is removed and the material is allowed to cool from the exterior thereof, the atmosphere being excluded therefrom by a protective cover disposed thereover before the furnace cover is lowered.

The present practice of annealing as described above requires a considerable amount of equipment such as furnace bases and a correspondingly large floor space, because of the time required for the material to cool from the maximum temperature to which it is heated, to a temperature at which atmospheric oxidation thereof does not proceed rapidly. The cost of this equipment, of course, is directly reflected in the cost of the finished product.

We have invented a novel apparatus for annealing material in coil form whereby the time required for a charge to cool may be substantially reduced. By reducing the length of the cooling stage of the annealing cycle, it is possible to process the same tonnage with less equipment, i. e., furnace bases, and floor space, than has been necessary heretofore, thus effecting a substantial reduction in the cost of the processing and the finished product.

In a preferred embodiment of our invention, a cover type furnace having a base is provided with one or more upstanding tubular guides adapted to center a stack of coils disposed thereover and connected to a supply of cooling fluid. The furnace base is also provided with means for circulating the atmosphere within the protective cover to cool the coils from the exterior thereof.

The apparatus of our invention will be described in detail hereinafter with reference to the accompanying drawing illustrating a preferred embodiment. In the drawing,

Fig. 1 is a vertical, central section through a cover type furnace, the base of which is constructed according to our invention; and

Fig. 2 is a partial horizontal section substan-

tially along the plane of line II—II of Fig. 1 with parts omitted.

Referring now in detail to the drawing, the furnace shown in Figs. 1 and 2 comprises an open-bottomed heating cover or bell 10 adapted to be removably disposed on a base 11. The cover 10 comprises a substantially cylindrical side wall 12 of refractory brick enclosed within a shell 13 of sheathing plates, and a flat roof 14 of refractory brick suspended from cross beams 15 to which a lifting block 16 is secured as by welding. An annular bottom plate 13a secured to the shell 13 and stiffened by gusset plates 13b carries the wall 12 and is adapted to engage a portion of the base 11 to be referred to later, when the cover is positioned thereon.

Curvilinear heat-exchange tubes 17 are mounted in spaced relation about the circumference of the cover with their intermediate portions exposed inwardly thereof and their end portions passing out through suitable openings in the side wall 12. The spaces between the tubes and these openings are closed by seals 18 and 19. A burner 20 extends into the lower end of each tube 17 and is connected to a circumferential fuel supply main or header 21 by a flexible pipe 22. The supply of fuel from the header 21 to each burner is controlled by a valve 23.

Spark-gap igniters 24 are secured to the tubes 17 adjacent their upper ends and connected to energizing transformers 25 mounted on the exterior of the side wall of the cover.

The base 11 comprises a structural frame 26 including a bottom plate 27 and a central cylinder 28. A charge-supporting hearth 29 is built up of refractory brick on the bottom plate 27. A peripheral sealing channel 30 extends around the hearth 29 and has a partition 31 disposed concentrically therein providing a pair of adjacent annular containers for sealing liquid.

The hearth 29 is provided with a cover 32 of heat-resistant alloy such as chromium steel. The outer edge of this covering extends downwardly between the inner wall of the channel 30 and the partition 31 and below the surface of the sealing liquid contained therein.

A charge-support 33, preferably in the form of a casting of heat-resistant alloy is disposed on the hearth 29, on top of the cover 32 thereover. The support 33 is in the form of a hollow annulus of box section having openings 34 in the vertical walls thereof and openings 35 in the horizontal walls. A grille 36 of heat-resistant alloy is removably disposed over an opening in

the center of the upper horizontal wall of the casting.

Upstanding tubular guides 37 extend upwardly above the support 33 and are spaced circumferentially thereof. Each guide 37 comprises a length of pipe closed and tapered at its upper end and detachably secured by a coupling 37a to a tube 38 preferably of heat-resistant alloy, embedded in the hearth 29 and threaded into a coupling 39 welded to the bottom plate 27. The 10 guide 37 itself may be of ordinary steel pipe since it can readily be replaced on deterioration. A second length of pipe 40 is threaded into the coupling 39 and has a closure 41 welded to the end thereof. The closure 41 has a hole therethrough which is tapped to receive a pipe 43 extending upwardly through the guide 37. An extension 42 of the pipe 40, is welded to the closure 41 at one end, its other end being closed. Radial connections 44 and 45 permit cooling fluid such as 15 water to be circulated upwardly through the pipe 43 and downwardly through the guide 37.

The coils of material to be annealed are stacked and lowered over the centering guides 37. In the drawing, we have illustrated as the material being processed, wire coiled on metal reels 46. As shown in the drawing, each reel 46 comprises a central tube 47, an annular channel 48 and discs 49 extending between the tube and channel and welded thereto. The tube 47 has an inside diameter sufficiently greater than the outside diameter 30 of the guide 37 to facilitate positioning of the reels on the support 33 and their removal therefrom.

When stacked reels have been lowered over the guides 37 and onto the support 33, as shown in Fig. 1, the cover 10 being raised from the base during the loading operation, a protective cover 50 is lowered over the charge. The cover 50 is an open-bottomed enclosure of metal plate having a downwardly flaring portion 51 adapted to lie between the hearth 29 and the bottom of the cover when the latter is lowered into position so that its bottom plate 13a rests on the outer wall of the channel 30 which is stiffened by gussets 45 to adapt it for supporting the cover. The protective cover 50 has bottom flanges 52 and 53 adapted to extend downwardly into the sealing channel 30 on opposite sides of the partition 31 and rest on the bottom thereof. After the protective cover 50 has been placed over the charge, the heating cover 10 is lowered to the position in which is it shown in Fig. 1.

The annealing operation for which our apparatus is adapted is usually a continuous process, the burners 20 in the tubes 17 of the cover 10 being fired steadily so that heating of the charge starts immediately on lowering of the cover. As previously indicated, furthermore, the cover 10 cooperates successively with a number of different bases whereby while the cover is heating a charge on one base, the charge on another base is cooling and a charge is being removed from or disposed on still other bases.

The tubes 17, being heated to radiant temperature by the combustion gases traversing them, radiate heat to the protective cover 50 which in turn radiates heat to the coiled material on the reels 46. To expedite heating of the material to the desired temperature, we provide an impeller 54 mounted on a shaft 55 extending vertically through the center of the hearth 29. The shaft 55 extends upwardly from a motor reducer 56 disposed in and secured to the cylinder 28. It will be apparent that when the impeller 54 is

driven, it tends to circulate the atmosphere within the protective cover 50 outwardly through the openings 34, upwardly along the side wall of the cover 50 and downwardly along the axis of the base and cover and through the grille 36. Any desired atmosphere may be maintained within the cover 50 by means of connections 57 and 58. Usually a deoxidizing atmosphere is desirable.

When the charge has been heated to the desired temperature as determined by a thermocouple 59, the cover 10 is lifted and disposed on another base whereon the next succeeding charge has been placed. Cooling of the charge on the base 11 then occurs by radiation from the coils on the reels to the cover 50 and atmospheric cooling of the latter. If the impeller 54 is operated during the cooling stage, cooling of the coils is effected by convection, the atmosphere within the cover 50 circulating as already explained around the stacked coils and transferring heat to the cover 50 by convection.

Cooling water is supplied through the connection 44 and the pipe 43, by operating suitable control valves. The cooling water flows out through the pipe 43 into the interior of the guide 37. The water will be partially or wholly vaporized and the vapor and water, if any, are taken off through the connection 45. The circulation of cooling water through the guides 37 serves to cool the interior of the stacked coils effectively, the heat being transferred from the coils on the reels to the guides by radiation. The heat absorbed from the interior of the coils, of course, is disposed of by the downward flow and discharge of the water delivered to the interior of the guides.

By cooling the interior of the coils, the cooling stage of the annealing cycle is materially shortened and the entire processing operation expedited. As a matter of fact, the cooling stage is shortened sufficiently to make it possible to carry on a continuous processing operation with only three bases for each cover, instead of four as required heretofore. This reduces the cost of the equipment necessary to process a given monthly tonnage. Since only three bases are required, the amount of necessary floor space is also reduced. All these results contribute to a reduction in the cost of the finished product.

A further advantage resides in the fact that by cooling the coils interiorly as well as exteriorly, a greater uniformity of the characteristics of the product is obtained since all portions of the coils cool at more nearly the same rate than when treated according to the prior practice.

By making the coupling 37a of steel, the difference between the coefficient of thermal expansion thereof and that of the alloy tube 38 causes the joint therebetween to tighten on heating, decreasing the possibility of leakage at the point where the guides 37 are removably attached to the remainder of the fluid circulating system.

Although we have illustrated but a preferred embodiment of the invention, it will be understood that changes in the apparatus disclosed herein may be made without departing from the spirit of the invention or the scope of the appended claims.

We claim:

1. A furnace base adapted to receive material in coils for enclosure by a heating cover, said base including a coil support, an upstanding tubular guide tapering to a point at its upper end, rigidly attached to said base and thereby adapted to center coils disposed on the support,

and connections for supplying cooling fluid to said guide.

2. A furnace base adapted to receive material in coils for enclosure by a heating cover, said base including a coil support, a tube extending through said base, a hollow guide tapering at its upper end, communicating with said tube and rigidly mounted thereon and thereby adapted to center coils disposed on the support, and connections for supplying cooling fluid to said tube.

3. A furnace base as defined by claim 2 characterized by said guide being detachably connected to said tube.

4. A furnace base adapted to receive material in coils for enclosure by a heating cover, said base including a coil support, an upstanding tubular guide rigidly mounted on said base and thereby adapted to center coils disposed on the support, a pipe extending through said guide substantially to the upper end thereof, and cooling fluid connections to said guide and pipe.

5. A furnace base adapted to receive material

in coils for enclosure by a heating cover, said base including a coil support, an upstanding tubular guide rigidly mounted in said base and thereby adapted to center coils disposed on the support, a closure at the lower end of said guide, a pipe extending upwardly from said closure into said guide, an extension on said guide below said closure, and cooling-fluid pipes threaded radially into said guide and extension above and below said closure.

6. A furnace base adapted to receive material in coils for enclosure by a heating cover, said base including a coil support, means below said support for circulating the atmosphere surrounding said coils, hollow coil guides extending from said base through and above said support and spaced circumferentially about said means, and connections for circulating cooling liquid through the coil guides.
